LOCOMOTIVE BOILER

Filed Aug. 17, 1929

Inventor:
Walter M. Winsch.

Rev. Arthur W. W. Moore

UNITED STATES PATENT OFFICE

WALTER H. HINSCH, OF CHICAGO, ILLINOIS, ASSIGNOR TO LOCOMOTIVE FIREBOX COMPANY, OF CHICAGO, ILLINOIS, A CORPORATION OF DELAWARE

LOCOMOTIVE BOILER

Application filed August 17, 1929. Serial No. 386,665.

This invention relates to improvements in locomotive boilers and it consists of the matters hereinafter described and more particularly pointed out in the appended claims.

5 The primary object of the invention is to provide in a thermic siphon equipped locomotive boiler, a novel connection for the inlet end of said siphon, with a portion of the firebox sheet, which while being water tight will permit of that amount of movement 10 which said end takes on under temperature changes.

Still another object of the invention is to provide such a connection which though disposed between inner and outer sheet parts of the boiler, in no manner interferes with the cleaning and flushing out of said siphons.

These objects of the invention as well as others together with the many advantages 20 thereof, will more fully appear as I proceed with my specification.

In the drawings:—

Fig. 1 is a longitudinal vertical sectional view through the firebox end of a locomotive 25 boiler embodying my invention.

Fig. 2 is a fragmentary detail sectional view of parts shown in the lower right hand corner of Fig. 1 on an enlarged scale.

Referring now in detail to that embodiment 30 of the invention illustrated in the accompanying drawings, the boiler includes a firebox comprising a flue sheet 1, an inner rear sheet 2, and a crown sheet 3 extending therebetween. 4 indicates one of the side sheets of the firebox which includes a fire chamber 5 and a combustion 6 forward of the same. The bottom 7 of the combustion chamber is made as a continuation of the inner front throat sheet 8.

10 indicates the shell of the boiler, 11 the outer rear sheet therefor and 12 indicates the outer front throat sheet of the boiler. Several of the sheets mentioned provide the front water leg or throat 13, the rear water leg 14 and side water legs (not shown) all in communication with the boiler water space of the boiler and closed at their bottom end by the mud ring 15. The open bottom of the fire chamber 6 has the usual grate as indicated by the dotted line 16 and in the flue

sheet 1 are secured the usual flues 1^a through which the products of combustion pass on their way to the smoke box at the front end of the boiler. The construction described may be taken as typical of a present day locomotive boiler. 55

To increase the efficiency of boilers having fireboxes of this type, water steaming and circulating elements are employed both in the fire chamber and in the combustion chamber. Such elements usually are what have now become known as the Nicholson thermic siphons and each comprises a flat hollow body disposed longitudinally of the firebox and opening at one end through the crown sheet 60 and terminating at the other end in a tubular inlet neck; the neck of the siphon in the firebox opening through and being connected to the inner throat sheet 8 and the neck of the siphon in the combustion chamber opening through and being connected to the bottom wall 7 of the combustion chamber. 65

As the flat hollow body of the siphons presents a considerable heating surface area to the products of combustion, it is apparent 70 that a movement of the elements develops under changes of temperature. Heretofore, it has been attempted to accommodate such movement by forming annularly corrugated parts in the front throat sheet 8 and bottom 75 wall 7 of the combustion chamber to provide flexible diaphragms but the same do not permit that degree of flexibility desired or the accessibility necessary for easy cleaning and inspection purposes. 80

In Fig. 1 is illustrated in side elevation two of such siphons, each indicated as a whole by the numeral 17 and 18 respectively, with the former disposed in the fire chamber and the latter disposed in the combustion chamber. The number of siphons of course is dependent upon the size of the firebox and in some instances there is a plurality of such siphons in one or the other of said chambers. As shown herein for the sake of simplicity 90 and convenience only one siphon is shown in each chamber. The siphon 17 includes a flat hollow, staybolted body 17^a which is fixed in the rear part of the crown sheet 3 and opens therethrough, and a tubular inlet neck 17^b 95

disposed at substantially a right angle to the plane of the throat sheets 8 and 12 respectively with which it is associated. The siphon 18 includes a flat hollow staybolted body 18^a which is fixed in the front part of the crown sheet 3 and opens therethrough and a tubular inlet neck 18^b, the bottom end of which is disposed at substantially a right angle to the plane of the bottom wall 7 of the combustion chamber.

In the throat sheet 8 is provided an opening 20 and to the parts of said sheet within the fire chamber adjacent said opening is fixed a plate 21 through which the inlet end 13 of the siphon neck 17^b freely extends, the extremity of said neck having a metallic collar 22 of noncorrodible metal fixed thereon. 23 indicates an annular plate disposed in the opening 20 in the throat sheet 8, so as to surround the collar 22.

The top end of said annular plate is flat and is there provided with an annular groove 24 to receive an annular compressible gasket or ring 25 that engages directly against the adjacent face of the plate 21. The bottom surface of the plate 23 is provided with a convexed recess 26 in which snugly seats a compressible gasket or packing 27 which surrounds and is in direct engagement with the collar 22 on the inlet neck 17^b of the siphon 17.

A helically coiled expansion spring 28 surrounds the extremity of said neck and collar and engages at one end against the packing ring 27 and engages at its other end against a reinforcing seat plate 29 on the inner face of the outer throat sheet 12. Said plate has lugs 30 to prevent lateral movement of the spring 28 and a washout plug 31 is threaded through the sheet 12 into said plate.

In the bottom wall 7 of the combustion chamber is formed an opening 20^a in which is welded a cup shaped member 29^a disposed in the water space of the boiler between said combustion chamber bottom wall 7 and the shell 10. This cup shaped member has both a bottom and side openings 29^b and 29^c respectively whereby communication is afforded between said water space and the interior of said cup shaped member. Associated with the flanged top end of said cup shaped member is a plate 21^a having a central opening therein, down through which the end of the siphon neck 18^b extends. On said neck is secured a collar 22^a of noncorrodible metal.

Surrounding said collar is an annular plate 23^a having a flat top face in which is formed an annular groove 24^a. Disposed in said groove is a packing ring or gasket 25^a which engages with the bottom surface of the plate 21^a. In the bottom surface of the annular plate 23^a is formed a concaved seat 26^a in which seats an annular packing ring 27^a snugly fitting upon the collar 22^a. A helical expansion spring 28^a surrounds the extremity 65 of the collar 22^a and engages at one end

against said packing ring 27^a and engages at its other end against the bottom wall of the cup shaped member 29^a which is formed in a manner preventing lateral shifting of said spring 28^a.

It is apparent that in both instances a connection is provided for each inlet neck end whereby movement thereof in two different planes is provided and this without leakage.

By reason of the spring 28, it is apparent that the packing ring 27 is compressed and due to the convex seat in which it is engaged, it tends to crowd into a snug fit about the collar 22. This action of the spring 28 also urges the annular plate 26 toward the plate 21 thus compressing the packing ring 25^a to there provide a tight joint. Should the movement of the neck be slightly laterally the packing 27 will shift in the seat 26 to accommodate such movement.

As the parts associated with the inlet neck 18^b are substantially the same, the corresponding parts will accommodate the movements taken by said neck.

The construction described, is efficient in operation and will automatically take up such wear as develops in the packings so that they are at all times water tight.

While in describing my invention, I have referred in detail to the form, arrangement and construction of the several parts thereof, the same is to be considered merely as illustrative so that I do not wish to be limited thereto except as may be specifically set forth in the appended claims.

I claim as my invention:

1. A locomotive boiler having a firebox, a water steaming and circulating member disposed in the firebox and having a tubular inlet end opening through one of the sheets thereof so as to communicate with the water space of the boiler and means associated with said sheet and including a packing surrounding said inlet end and providing a connection for said inlet end which permits of both a longitudinal and a lateral movement of said neck without leakage about the same.

2. A locomotive boiler having a firebox, a water steaming and circulating member disposed in the firebox and having a tubular inlet end opening through one of the sheets thereof so as to communicate with the water space of the boiler, a plate fixed with respect to said sheet of the firebox, an annular plate in close proximity to said first mentioned plate and movable with respect thereto, and which annular plate has an annular concaved seat therein surrounding said inlet end of said water steaming and circulating member,

a packing disposed between said plates, a second packing disposed in said annular concaved seat and a means exerting a pressure upon both packings and causing said second packing to closely engage in said seat upon said inlet end.

3. A locomotive having a firebox including a fire and a combustion chamber, a thermic siphon in each chamber and each including an elongated discharge end opening thru the 5 crown sheet and a tubular inlet end opening through the front sheet of the fire chamber and the bottom wall of the combustion chamber respectively, and means arranged in the water space of the boiler and associated with 10 said throat sheet and bottom wall respectively and surrounding said inlet ends and providing a connection for said inlet ends permitting of both a longitudinal slip movement and a lateral movement of said inlet ends 15 said means in each instance including a packing.

4. A locomotive boiler having a firebox, a plate fixed with respect to the inside of one of the sheets thereof and which plate has an 20 opening therein, a water steaming and circulating member in the firebox and having a tubular inlet end extending through said plate opening into the water space of the boiler, a ring surrounding that part of said inlet 25 end in said water space, a packing between said ring and plate, a second packing between said ring and said inlet end and means acting upon said second packing in connection with said ring for causing said second packing to 30 normally contract upon said inlet end and to compress the first mentioned packing between said plate and ring.

In testimony whereof, I have hereunto set
my hand, this 13 day of August, 1929.

35 WALTER H. HINSCH.
